Specification for Design.

Patented Aug. 29, 1916.

Application filed June 21, 1916. Serial No. 105,071. Term of patent 3½ years.

D To all whom it may concern:

Be it known that I, JANE G. STOKES, a citizen of the United States, and a resident of the city of New York, borough of Manhattan, in the county and State of New York, have invented a new, original, and ornamental Design for a Doll, of which the following is a specification, reference being had to the accompanying drawing, forming part thereof.

Figure 1 is a front view of a doll showing the design; and Fig. 2 is a side view.

The essential feature of my design is the general hour-glass shape of the doll when viewed from in front or the rear, the upper part being smaller than the lower, and the face of the doll appearing at the narrow or contracted part of the doll.

I claim:

The ornamental design for a doll, as shown and described.

JANE G. STOKES.
